UNITED STATES PATENT OFFICE.

JOSEPH W. BISHOP, OF MUSKEGON, MICHIGAN, ASSIGNOR TO THE BRUNSWICK-BALKE-COLLENDER COMPANY, OF WILMINGTON, DELAWARE, A CORPORATION OF DELAWARE.

COMBINED PHONOGRAPH AND RADIO RECEIVING APPARATUS.

Application filed June 30, 1924. Serial No. 723,115.

This invention relates to a combined phonograph and radio receiving apparatus and has for its object to provide such an apparatus which may employ a single amplifying horn, such as that normally found in a phonograph, for use with a radio receiving set. This invention may be embodied in a cabinet similar to that shown in the application of Martin Nystrom, Serial No. 713,128, filed 10 May 14, 1924, or it may be incorporated in any other cabinet or similar structure.

More specifically the object of my invention is to provide an amplifying horn adapted to be placed in operative relationship with either a phonograph or a radio receiving set, and employing a valve operable from a control on the motor-board for switching from the phonograph to radio, or vice versa.

Another object is to provide a means for connecting the amplifying horn to either a phonograph or a radio set, which shall be inexpensive to manufacture but efficient in operation.

In the drawings in which I have shown one embodiment of my invention,

Fig. 1 is a plan of the top of a cabinet containing a phonograph and a radio receiving set, the cover of the cabinet being shown in raised position.

Fig. 2 is a section on the line 2-2 of Fig. 1.

Fig. 3 is a section on the line 3-3 of Fig. 1.

Fig. 4 is a plan of the neck connecting the amplifying horn to the phonograph and radio set, together with the valve employed therewith.

Referring now to the drawings, the numeral 1 designates a cabinet of any suitable construction and containing a radio receiving outfit 2 of any desired kind, and a phonograph 3. The phonograph comprises the usual turn-table 4, reproducer 5 and tone-arm 6. The radio receiving set includes a suitable loud speaker 7. Mounted in the cabinet is the amplifying horn 8 of a construction similar to that commonly used with phonographs and connected to the bell mouth of the horn in any suitable manner is a T-shaped hollow neck 9. This neck 9 has an arm 10 connecting with the bell mouth of the amplifying horn 8 and in this embodiment the arm 10 is horizontally disposed in the cabinet and extends rearwardly from the horn 8. The

neck is preferably bent upwardly from the arm 10 to form a vertically disposed sleeve 11. Connected with the sleeve 11 are two arms 12 and 13, in this embodiment shown extending horizontally from the sleeve 11 and from opposite sides thereof. The arm 12 is connected to the loud speaker 7 and the arm 13 is bent upwardly and connected to the tone-arm 6 extending through the motor-board 14.

It will be evident that sounds emanating from either the phonograph or the radio set may pass through the arms 12 or 13, as the case may be, into the arm 10 and to the amplifying horn 8.

Revolutely mounted in the sleeve 11 is a valve 15 comprising an elbow 16, the lower end 16' of which is adapted to register with the lower end of the sleeve 11 so as to form a continuous passage to the arm 10 and the amplifying horn. The other end 16'' of the elbow 16 is adapted to be brought into registry with the end of the arm 12 or arm 13, at will. Referring to Fig. 2, the elbow 16 is shown in position to receive sounds from the phonograph through the tone-arm 6 and 80 a phonograph and an amplifying horn, 8, and it will be apparent that there is a smooth, continuous passage provided for the sound. When the elbow 16 forming the valve is turned to a position, in this embodiment diametrically opposite to that shown in Fig. 2, the upper end of the elbow will be in registry with the end of the arm 12 which, it will be observed, is of the same size as the end of the arm 13, whereby a smooth, continuous passage will be provided from the loud speaker 7 to the amplifying horn 8.

On the part of the valve 15 opposite to the opening 16'' I provide a wall 17 to close the opening in the arm 12 or 13, as the case may be, thereby insuring the shutting off of sounds from one source while receiving sounds from another source. The wall 17 is part of a tube which fits within the walls of the sleeve 11 and is interrupted only by the opening 16'', thereby providing ample bearing surface for the valve.

I prefer to operate my valve from the motor-board and for that purpose I arrange the neck so that the end of the sleeve 11 will face the motor-board, that is, the sleeve 11 will be perpendicular to the motor-board. Integral with the elbow 16 of the valve 15 is

a slotted lug 18 and received within said slot is a flattened end of a rod 19 extending upwardly through the motor-board and provided at its upper end with a handle 20.

6 The turning movement of the valve is effected, as will be evident, by merely turning the handle or knob 20, and this movement of the valve is limited by means of a pin 21 projecting from the valve 15 and engaging shoulders 22 at the end of an arcuate slot 23 in the top of the sleeve 11.

10 From the above it will be apparent, that I have provided a means whereby one amplifying horn may be made to do service with either a radio receiving set or a phonograph, and wherein the change from one to the other may be effected by a mere turn of a knob on the motor-board, which will turn the valve 15 about its vertical axis. This means may also be used, as will be apparent, to vary the 15 volume of sound emanating from either the phonograph or the radio set, as the case may be.

15 I am aware that changes in the form, construction and arrangement of parts may be made without departing from the spirit and without sacrificing the advantages of the invention and I reserve the right to make all such changes as fairly fall within the scope 20 of the following claims.

25 I claim:—

1. In a device of the character described, a motor-board, a phonograph, a radio loud speaker, an amplifying horn, a neck having arms connected to said phonograph, said loud speaker and said horn respectively, a valve in said neck to operatively connect said horn with either said phonograph or said loud speaker, selectively, said valve being located 30 between and independent of said arms and free from said phonograph, loud speaker and horn, and operating means for said valve extending through said motor-board.

40 2. In a device of the character described, a motor-board, a phonograph, a radio loud speaker, an amplifying horn, a neck having arms connected to said phonograph, said loud speaker and said horn respectively, a valve in said neck to operatively connect said horn with either said phonograph or said loud speaker, selectively, said valve being located 45

between and independent of said arms and free from said phonograph, loud speaker and horn, operating means for said valve extending through said motor-board, and means for 55 limiting the movement of said valve.

3. In a device of the character described, a neck comprising a sleeve having arms adapted to be connected to an amplifying horn, a radio loud speaker, and a phonograph respectively, a valve revolvably mounted in said sleeve independently of said arms and adapted to form a passage from said horn to either said phonograph or said loud speaker selectively, said valve having a wall to close the 60 opening in the arm not in communication with the horn.

4. In a device of the character described, a T-shaped neck comprising arms adapted to be connected to an amplifying horn, a radio loud 65 speaker, and a phonograph respectively, and comprising a sleeve, a valve revolvably mounted in said sleeve and adapted to form a passage from said horn to either said phonograph or said loud speaker selectively, and means 70 for limiting the movement of said valve comprising an arcuate slot in said sleeve and a pin on said valve moving in said slot.

5. In a device of the character described, a motor-board, a T-shaped neck having arms 75 adapted to be connected to a radio loud speaker, a phonograph and an amplifying horn, respectively, a sleeve having an open end facing the motor-board, a valve revolvably mounted within said sleeve and adapted to form continuous passages from said horn to said phonograph or said loud speaker, selectively, and means to operate said valve and extending through said motor-board.

6. In a device of the character described, a 80 motor-board, a T-shaped neck having arms adapted to be connected to a radio loud speaker, a phonograph and an amplifying horn, respectively, a sleeve having an open end 85 facing the motor-board, a valve revolvably mounted within said sleeve and adapted to form continuous passages from said horn to said phonograph or said loud speaker, selectively, means to operate said valve and extending through said motor-board, and means 90 to limit the movement of said valve.

JOSEPH W. BISHOP.
